UNITED STATES PATENT OFFICE.

EUGENE O. PERRY, OF DETROIT, MICHIGAN.

BROODER.

1,215,982.

Specification of Letters Patent. Patented Feb. 13, 1917.

Application filed October 23, 1916. Serial No. 127,225.

To all whom it may concern:

Be it known that I, EUGENE O. PERRY, a citizen of the United States, residing at Detroit, in the county of Wayne and State of Michigan, have invented certain new and useful Improvements in Brooders, of which the following is a specification, reference being had to the accompanying drawings.

This invention relates to improvements in brooders and has for its primary object to provide a poultry brooder having a brooding chamber and a feed chamber, said brooder being of such construction that the said chambers can be bodily removed from connection with the base or floor of the brooder, whereby the latter can be conveniently swept or cleaned.

It is another important object of my invention to provide a sectional brooder for poultry, one of said sections having a brooding and feeding chamber provided with transparent windows in the roof or top walls thereof, a hover arranged in the brooding chamber, and a heater therefor, the base portion of the apparatus being provided with a suitable door through which a lamp or other heating medium may be arranged therein beneath said heater.

It is an additional object of my invention to provide a device of the above character which is of simple and inexpensive construction, highly serviceable and convenient in practical use, and is admirably adapted for the purposes in view.

With the above and other objects in view, my invention consists in the novel features of construction, combination and arrangement of parts to be hereinafter more fully described, claimed and illustrated in the accompanying drawing, in which,

Figure 1 is a perspective view of a brooder constructed in accordance with the preferred embodiment of my invention;

Fig. 2 is a longitudinal section thereof; Fig. 3 is an enlarged vertical section through the heater;

Fig. 4 is a horizontal section thereof taken on the line 4—4 of Fig. 3; and,

Fig. 5 is a bottom plan view of the heater. Referring in detail to the drawings, 5 designates the base section of my improved brooder which may be of any desired dimensions and is provided at one end with an inclined runway 6. A suitable door 7 is provided in one of the side walls of this base section 5, adjacent to its opposite end.

The top section 8 of the brooder is divided by a transverse partition wall 9 into a brooding chamber 10 and a feeding chamber 11. To the side walls of this section 8 of the brooder, at each end thereof and adjacent their lower edges, hooks 12 are attached for engagement with suitable eyes secured to the side walls of the base section 5. The roof of the removable section 8 is transversely inclined in opposite directions from a central ridge 13, and upon each side of this ridge, hinged, transparent windows 14 are suitably mounted over the brooding chamber 10 and the feed chamber 11. Spaced, transversely disposed, vertical walls 15 connect the side walls of the base section 5 to afford additional strength and also to support the floor 17 of the brooding and feeding chambers.

The floor of the brooding chamber 10 has an opening 18 therein, and a heater generally indicated at 19 and preferably of rectangular form is arranged in the brooding chamber, the bottom wall of said heater having an opening 20 therein coinciding with the opening 18 in the brooder floor. The heater includes an outer wall and an inner wall 21 which is entirely closed and spaced from said outer wall, as seen in Fig. 3. The inner wall is sustained in such spaced relation by a number of brackets indicated at 22 fixed to said inner and outer walls. An outlet pipe or conduit 23 is slidably engaged with the flue 23' connected to the top of the outer wall of said heater, and extends upwardly through an opening in the roof ridge 13. A hover board 24 is supported above the heater in spaced relation thereto, said board likewise being of rectangular form and having a plurality of depending, fabric strips 25 attached to its outer edge. 26 indicates the lamp or other suitable heat producing means which is inserted through the door in the side of the base section 5 beneath the opening 18. The heat rising from this lamp enters the space between the inner and outer walls of the heater and the outer wall thereof soon becomes heated to a high degree. The chicks gather closely around the hover so that they are warmed by the heat radiating from the heater. The partition wall 9 is provided with one or more doors, indicated at 27, which may be opened to admit the chicks into the feeding chamber 11, and the front end wall of the removable section 8 is provided with a door 28 to permit the

chicks to pass from the latter chamber to the yard.

From the foregoing description, taken in connection with the accompanying drawings, the construction, manner of operation and several advantages of my invention will be clearly and fully understood. By the provision of the square or rectangular heater, the chicks, in gathering around the 10 heater, will follow in a straight line along the side walls of the heater, and separate at the corners thereof so that they will not become tightly crowded together which might possibly result in the killing of some of the 15 chicks. The entire top section 8 may be very easily and quickly removed for the purpose of cleaning the floor 17 which, it will be noted, is permanently secured upon the edges of the vertical walls of the base section 5 and 20 to the transverse walls 15 and 16. The lamp may also be readily removed from beneath the heater through the door 7 for the purpose of cleaning or adjusting the same. While I have shown in the accompanying 25 drawing a particular construction of the heater and the hover, it will be understood that the manner of assembling the parts of the heater and the hover may be considerably varied. The several other detail features of the device are also susceptible of 30 considerable modification and I, therefore, reserve the privilege of adopting all such legitimate changes as may be fairly embodied within the spirit and scope of the invention as claimed.

Having thus fully described my invention, what I desire to claim and secure by Letters Patent is:—

1. In an apparatus of the character described, a base section having a top wall, an 40 upper section having brooder and feeding chambers isolated from each other, said top wall of the base section constituting the

floor of said chambers, exterior means for detachably holding the upper section in connection with the base section, a rectangular heater centrally arranged within the brooder chamber upon said floor, means for supplying heat to the heater, a hover supported upon the heater in spaced relation thereto, 50 said heater having an outlet flue, and a discharge conduit telescopically engaged upon the outlet flue and having its upper end secured in the top of said upper section.

2. In an apparatus of the character described, a base section having a top wall, an upper section provided with a transverse partition dividing the same into brooder and feeding chambers, doors in said partition wall affording communication between said chambers, means for detachably holding the upper section upon the base section, the top wall of the latter section constituting the floor of said chambers, the floor of the brooder chamber having an opening therein, 65 a heater having inner and outer spaced walls, the bottom of the outer wall being provided with an opening coinciding with the opening in said floor, a flue communicating with the space between said walls at the 70 top of the heater, said bottom section having a door in one of its side walls providing means for the insertion of a lamp beneath the heater, a hover supported in spaced relation to the heater, an outlet pipe permanently connected to the top of said upper chamber and telescopically engaged with said flue, and transparent windows mounted in the top of said upper section to afford access to said chambers.

In testimony whereof I hereunto affix my signature in the presence of two witnesses.

EUGENE O. PERRY.
